UNITED STATES PATENT OFFICE.

MELVIN B. HINDS, OF MEDFORD, AND HENRY A. SKINNER, OF MALDEN, MASSACHUSETTS; SAID SKINNER ASSIGNOR TO SAID HINDS.

COIN STACKING AND PACKING DEVICE.

1 280,031.

Specification of Letters Patent. Patented Sept. 24, 1918.

Application filed December 29, 1916. Serial No. 139,636.

To all whom it may concern:

Be it known that we, MELVIN B. HINDS and HENRY A. SKINNER, citizens of the United States, residing at Medford, Malden, respectively, in the county of Middlesex, Middlesex, respectively, and State of Massachusetts, Massachusetts, respectively, have invented new and useful Improvements in Coin Stacking and Packing Devices, of which the following is a specification.

This invention relates to a coin stacking and packing device, whereby coins of any certain denomination, and aggregating any given amount, may be quickly and conveniently collected, stacked and wrapped.

The object of the invention is to provide a simple, efficient and inexpensive construction of device, which may be conveniently applied to a counter or table, so as to receive coins as counted and assemble the same in the form of a stack and simultaneously deposit the coins in a wrapper, which may be conveniently removed and sealed.

A further object of the invention is to provide a device of this character which may be used in connection with stacking and wrapper holding tubes of different sizes for coins of different denominations, which may be applied to a table or counter in such a manner as to leave the hands of the operator free to count and shove therein the coins to be stacked, and which is sufficiently economical in construction to adapt it to be manufactured and sold at small cost for the use of small banks and stores which do not have a sufficient volume of business to warrant the purchase of large and expensive sorting and stacking devices.

The invention consists of the features of construction, combination and arrangement of parts hereinafter fully described and claimed, reference being had to the accompanying drawing in which:

Figure 1 is a top plan view showing the device applied for use to a table or counter, a portion of the table or counter being shown.

Fig. 2 is a section on the line 2—2 of Fig. 1.

Fig. 3 is a rear perspective view of the hopper detached.

Fig. 4 is a view showing in section a series of stacking tubes adapted for interchangeable use with the hopper.

In carrying the invention into practice, we provide a hopper or receptacle 1, of ob-

long rectangular form at its upper portion and thence having its end walls sloping downwardly and inwardly to form a central circular outlet 2 at the bottom thereof, said outlet being adapted to receive the upper end of a stacking tube 3, as hereinafter fully described.

The rear wall 4 of the hopper is cut away at its top, so that its upper edge is below the plane of the front wall 5 of the hopper, and said rear wall 4 is provided with a pair of spaced abutment lugs 6 extending horizontally and rearwardly therefrom and flush with the upper edge of said wall. The end walls 7 of the hopper are also cut away at their rear portions adjacent to the ends of the upper edge of the wall 4 to provide receiving spaces 8, and said walls are further provided with supporting arms or projections 9 disposed beyond the ends of the upper edge of the wall 4 and provided with down-turned flanges or hooks 10.

The hopper is adapted to be applied for use upon one of the margins or edges of a counter or table 11, to which end a supporting plate 12 is provided, secured to the underside of the counter or table by suitable fastenings 13 and having its forward edge projecting beyond the edge of the counter or table and extending upwardly in the form of a flange 14 to form a channel or grooved guideway 15. This plate and the grooved guideway or channel formed thereby may be of any suitable length, so that the hopper may be slidably adjusted to different positions along the length of the table as desired for use.

In applying the hopper, the hopper is disposed at such an angle as to bring the rear edge of its rear wall and the abutment lugs beneath the supporting plate and the hooked arms 9 above the channel or guideway 15, whereupon by tilting the hopper downwardly and rearwardly the hopper will be disposed in position for use. In such position, it will be seen that the hooked arms will rest upon and engage the guideway, while the abutment lugs will extend under the table and bear thereagainst and thus coöperate with the hooked arms to support the hopper in position in close proximity to the adjacent edge or margin of the counter or table. By reverse tilting and upward motion of the hopper, it will be understood that it may be disconnected from the counter or table, so

that it may be removed and stored away when its use is not desired. By sliding the hopper in position from either end of the guideway, the hopper may also be readily 5 and conveniently applied and removed, in an obvious manner.

For use in connection with the hopper we may provide any desired number of stacking tubes 3 of different lengths and diameters, as shown in Fig. 4, for the reception of coins of different diameters and denominations, or for stacking different amounts of coins of the same denomination. Each of these tubes is provided with an enlarged 10 or expanded mouth portion 16 at its upper end, which is adapted to fit within the discharge outlet 2 of the hopper, and has its marginal edge 17 slightly out-turned or flared to rest upon a beveled abutment 15 surface 18 at the base of the hopper immediately above the outlet 2, whereby the tube 3 is adapted to be inserted downwardly from above into receiving position and to be supported by the edge 17 resting against the 20 surface 18. The lower end of each tube is also provided with an out-turned portion 19 to facilitate the insertion and removal of wrappers 20 made of paper or other suitable material, and in which the coins are 25 designed to be stacked and wrapped in prescribed amounts. Each tube 3 is further provided with an internal shoulder 21 to limit the upward insertion of the wrapper 20.

30 Each wrapper 20 is of tubular form, and adapted to be suitably folded and closed at its upper and lower ends. By the use of wrappers of different sizes in connection with tubes of different sizes coins of different denominations, aggregating any given 35 amount, may be stacked or filed within each wrapper and sealed, and the amount marked in any suitable manner upon the wrapper.

In the use of the device, it will be under-

stood that it is applied in the stated manner 45 to the edge of a table or counter on which the operation of counting and stacking is to be performed, the device being within convenient reach of the operator, who, as he counts the coins, may sweep or shove them 50 into the hopper, from which they will fall in proper order into the inserted wrapper 20. This wrapper 20 is inserted into the stacking tube from below, and its lower end may be preliminarily folded or closed, and 55 after the prescribed number of coins have been deposited therein the wrapper may be withdrawn and its upper end folded or closed, thus confining the stack or column of coins against loss or displacement. As before stated, the device may be removed from the table or counter whenever desired and conveniently stored away until its use is again required, and such device provides a simple, convenient and inexpensive article 60 for the use of small stores and banks in which the volume of business is not such as to justify the use of expensive counters and stackers.

We claim:—

1. A device of the character described comprising a hopper, a stacking tube removably connected with the hopper and adapted to receive a coin wrapper, and spaced lugs and projections carried by the hopper for 75 detachably connecting said hopper with the edge of a counter or table.

2. A device of the character described comprising a hopper, sets of holding devices upon the hopper for tiltably and detachably 80 connecting it with a support, the said sets of devices extending from the hopper at points lying in different planes, and a stacking tube detachably connected with the hopper.

In testimony whereof we affix our signatures.

MELVIN B. HINDS.
HENRY A. SKINNER.
